RAYON SPINNING MACHINE

John B. Dove, Atlanta, Ga., assignor of forty-nine
per cent to Lee Roy Muse

Application July 17, 1936, Serial No. 91,197

12 Claims.

Generically this invention relates to spinning machines, but it is particularly directed to machines for spinning rayon or other synthetic material by means of which the thread-like product is expeditiously produced and predeterminedly wound uniformly on suitable spools.

Considerable difficulty has been experienced in the past in effecting a fine thread from wood pulp and the like having a uniform gauge and at the same time in a volume sufficient to insure a maximum production at a minimum of cost, therefore, one of the important objects of this invention is to simplify the operating components of the machine and at the same time effect a positive driving assembly and coordination of interrelated parts, adapted to produce individual multifilament yarns of fine texture from pine pulp cellulose or other suitable material, of nonvariable gauge, at a greatly increased spindle winding speed to increase the volume of production, at a decrease in production cost.

Another important object of this invention is the provision of a simplified and positive mechanism operable to control and effect a predetermined winding of the thread on the bobbins according to the desired number of threads per surface inch uniformly throughout the winding process and expeditiously settable to vary the number of strands per inch in accordance with particular operating requirements, as desired.

A further important object of this invention is the provision of means for controlling and altering the flow of the filament yarn from the spinnerets to compensate for variations in the surface winding of the yarn on the spools during the building up process and to maintain a uniform gauge thread at maximum production rate.

A still further important object of this invention is the provision of a rayon spinning machine embodying simplified and positive driving and thread winding mechanism adapted to greatly increase the R. P. M. of the bobbins or winding spindles to materially and definitely increase the thread production and wherein the construction and operation of the pump and spinnerets is such as to increase the volume of the thread product in accordance with the increased spindle thread winding speed, and at the same time maintain a uniform thread gauge so as to effect a uniform fine filament yarn at an increased machine output rate.

With these and other objects in view, which will become apparent as the description proceeds, the invention resides in the construction, combination and arrangement of parts, hereinafter more

(Cl. 18-8) fully described and claimed, and illustrated in the accompanying drawings, in which like characters of reference indicate like parts throughout the several figures, of which:

Fig. 1 is a side elevation of the machine.

Fig. 2 is a transverse section on the line 2—2 of Fig. 1.

Fig. 3 is a transverse section on the line 3—3 of Fig. 1.

Fig. 4 is an elevation on an enlarged scale of the ratchet mechanism.

Fig. 5 is a plane view of Fig. 4.

Fig. 6 is a section on the line 6—6 of Fig. 5.

Fig. 7 is a section on the line 7—7 of Fig. 6.

Fig. 8 is a section on the line 8—8 of Fig. 6.

Fig. 9 is a fragmentary vertical sectional detail through the bobbin drive wheel and mounting.

The rayon making machines with which I am familiar have proven deficient in many ways such as presenting costly, complex and cumbersome mechanisms, non-positive driving connections,

thereby rendering it difficult to maintain a uniform thread production and gauge, difficult of expeditious adjustment to effect variation in rate of production and thread sizes, and by virtue of apparent complex construction and non-positive

driving or operating connections it has been found impossible to effect a thread winding spindle rate of more than approximately 300 R. P. M. to produce a production rate sufficient for efficient operation

and at the same time produce a satisfactory product and without thread breakage, especially as to the finer textured yarns, and it was to overcome such deficiencies and provide a simplified,

compact structural arrangement including a positive driving connection from the main drive shaft to the winding spindles including unique bobbin

carriage mounting and driving means, cooperating pump and spinneret structures, thread bobbin winding means, the construction and interrelation-

ship of parts being such as to effect the flow of synthetic material from the spinneret automatically

variable in accordance with the winding speed of the bobbin, and such construction adapted to greatly increase the speed of the

thread winding spindles to 400 R. P. M. and even above that, without affecting the uniform gauge of the thread, and to wind the thread at a predetermined number per linear inch per predetermined time interval, that I designed the rayon or other synthetic material producing machine forming the subject matter of this invention.

In the illustrated embodiment characterizing this invention there is shown a supporting frame structure A comprising suitably connected frame

10

sections such as spaced standards 1, 2, and 3, crossbeams 4, 5, and 6, and brace beams 7 suitably connected to the crossbeams 5 and standards 1 and 3.

5 It is to be understood that the standards and beams may be increased or decreased and their arrangement varied according to the particular machine desired.

10 A supporting platform structure 8 suitably connected to crossbeam 4 at one end of the frame adapted to support motor 9 and connecting said motor and main drive shaft 10 is reduction gearing 11, said shaft 10 being journalled in bearing supports suitably mounted on crossbeam 15 6 connected by reduction gearing 12 with spindle driving shaft 13 supported by suitable mountings connected to standards 3 and which extends the full length of the machine. Mounted on said rod 13 at spaced intervals throughout its length are 20 spur gears 14 adapted to mesh with complementary worm gear elements 15 keyed or otherwise suitably secured to the ends of the respective spindles 16 extending at right angles to shaft 13 suitably journalled through crossbeam 6, as will be well 25 understood. Mounted on the opposite ends of the respective spindles 16 are friction drive wheels 17. Each of these wheels is adapted to frictionally rotate a respective spindle on which the thread is wound and which mechanism will hereinafter be described in detail.

30 Mounted on crossbeams 4 journalled in bearings suitably connected thereto is a cone pulley drive shaft 18. One end of said shaft is connected to the rear end of shaft 10 by reduction gearing 19, said shaft intermediate the cone pulley 20 mounted thereon and the end adjacent to gearing 19 is divided and connected by clutch mechanism 21 controlled by clutch handle 22 pivotally connected to bracket 23 suitably mounted on standard 2. Mounted on the free end of shaft 18 is gear 24 and also mounted thereon central of its length is reversing handle 25 terminating at one end in hand grip 26 and having mounted at its upper end pinion gear 27 adapted 40 to mesh with screw rod gear 28 and with gear 24 to effect driving connection between said gears. Angularly positioned with respect to gear 28 and meshing therewith is reversing gear 29 mounted on stub shaft 30 and also mounted on said shaft 50 30 adjacent gear 29 is a smaller gear 31 which when handle 25 is moved to engage pinion gear 27 with said gear 31 the screw 32 on the end of which is mounted gear 28 is driven in a direction reverse to the direction it is driven when gear 29 55 is only in mesh with gear 28, as will hereinafter more fully appear.

60 It is to be understood that gear screw rod 32 is formed with threads 33 and is threadedly engageable in gear 28, said gear 28 has one edge 60 extending in the slotted surface of guide block 34 mounted on standard 2 so that rotation of gear 28 effects longitudinal movement of screw rod 32 in one direction and when reversed in the opposite direction, therefore causing intermittent reciprocation of said rod as and for a purpose directly more fully appearing. The end of rod 32 opposite to gear 28 is formed with a block member 35 and is formed with a pair of vertically disposed rollers 36 adapted to engage the opposite edges 70 of belt 37 adapted to travel over cones 20 and 38 so that the reciprocating movement of rod 32 will cause shifting of belt 37 to increase or decrease the speed of the driven cone pulley 38 and the devices operated by it as hereinafter 75 scribed.

In alignment with cone pulley 20 is a cone pulley 38 mounted on shaft 39 which has one end journalled in supporting bracket 40 suitably secured to standard 2 and at its other end in bearing 41 suitably connected to crossbeam 6. 5 Mounted on shaft 39 adjacent bearing 41 is gear 42 adapted to mesh with gear 43 mounted on shaft 44 suitably journalled in bearing 45 similar to bearing 41 and mounted on the free end of shaft 44 is driving disc 46. A driving rod 47 is 10 pivoted as at 48 to disc 46 and the other end is pivotally connected as at 49, between the ends of the twin segmental bars 50, the upper ends of said bars 51 being free.

15 Slidably mounted between said bars 50 is slide block 52 with its flanged edges 53 engaging opposite edges of said bars and pivotally connected to said block and extending therethrough is a transmission reach rod 54 pivoted at one end as at 55 to the lower end of the lead and lap lever 56 keyed 20 or otherwise connected intermediate its length to shaft 57 journalled in supporting blocks 58 bolted or otherwise suitably secured to standards 2. The upper end of lap lever 56 is pivoted to one end of link 59, the other end of link 59 is pivotally connected to lug 60 suitably secured to thread guide reciprocating rod 61 mounted in vertical parallelism with spindle 16 between pairs of spaced circumferential grooved rollers 62 rotatably mounted on brackets 63 bolted or otherwise 30 suitably secured to crossbeam 6 and with one end having a hook or thread guide 64 which is adapted to reversibly wind thread 65 over bobbin or spool 66 as it is drawn from the chemical bath tank 67, as will directly more fully appear. 35

Since the driving connection from disc 46 to lap lever 56, as shown in Fig. 3, effects limited rotation or rocking of shaft 57, the drive for the other lead and lap levers, as shown in Fig. 2, can be direct from said shaft 57 thereby eliminating 40 the use of the disc, as shown in Fig. 3. It is to be understood, of course, that the direct disc drive may be employed with each of said levers 56, if desired.

45 The free end of transmission reach rod 54 extends beyond slide block 52 and is formed with reduced rod portion 68 and slidably mounted thereon is block 69 formed with an upstanding ear 70, to which is pivotally connected the lower end of threaded lift rod 71, the upper threaded 50 portion of which is adapted to threadedly engage in the threaded split nut 72 formed at its upper end with bevel head 73 and each of the split sections 74 are formed with an outwardly projecting lateral lug 75 pivotally mounted between the ears 76 formed at the lower edge of hub portion 77 of ratchet wheel 78 on opposite sides of bore 79. Mounted on split nut 72 are cup washers 80 and cup sleeve washer 81 adapted to form seats for spiral spring 82 also mounted 60 on said nut. The sleeve washer 81 is internally beveled as at 83 at its lower end to receive the complementary bevel head 73 which also constitutes a stop for said sleeve. The complementary meeting surfaces of the sections 74 slightly taper 65 outwardly towards their upper end so that when force is applied to sleeve 81 in spring compressing direction the sections 74 will expand permitting rod 71 to become disengaged from said nut, as will hereinafter more fully appear. 70

Said sleeve 81 is formed on opposite sides with pivot lugs 84 adapted to engage in openings in the ends of yoke arms 85 of yoke handle 86. Mounted on hub portion 77 is a plate 87 elongated at one side as at 88 on which is mounted 75

the spring control pawl 89 adapted to engage teeth 90 of ratchet wheel 78 to prevent back lash of said wheel, as will be apparent. Also mounted on said hub is a supporting plate 91 having a 5 perforated extension 92 adapted to seat against squared portion 93 of anchor pin 94 extending through frame member 3 and secured by nut 95. Said plate portion 92 is secured to bolt 94 by pin 96. It will thus be seen that bolt 94 and plate 10 91 connected by pin 96 support the split nut and ratchet wheel structure in such a manner as to permit rocking or reciprocating movement of said ratchet wheel in a manner and for a purpose directly appearing. Secured to frame member 15 3 is a pawl yoke plate 97 secured by bolts or in any suitable manner to frame member 3 and formed on its under surface with spring control pawls 98 projecting in opposite directions and so formed as to engage teeth 90 and effect 20 rotation of said ratchet wheel when same is rocked or reciprocated in a manner hereinafter more fully described. Lap hanger 99 extends between yoke arms 85 and is pivotally connected thereto by pin 100. The lower end of lap hanger 25 99 is pivoted at its lower end to bars 50 by pivot pin 52', its upper end being pivotally connected to pin 96 by connection 102. Stop element 103 engages arm 86 and maintains said arm and yoke in normal reciprocating position. Mounted on 30 lift rod 71 is a threaded adjustable collar 71' having a set screw 86'. Said collar is adapted to be set as desired to limit the upward movement of lift rod 71 and return said rod and connected parts to their initial positions when the bobbin 35 is full. When ratchet wheel 78 has rotated split nut 72 to effect elevation of lift rod 71 sufficiently to bring collar 71' into engagement with yoke arms 85 and as lift rod 71 moves upwardly yoke arms 85 are elevated compressing spring 82 thus loosening nut 72 and permitting lift rod 71 with 40 blocks 69 and 52 with their connected parts to fall to their original low or long stroke position, as will be hereinafter more fully explained.

It will thus be seen that disc wheel 46 through 45 segment bar 50, transmission reach rod 54 and lead and lap lever 56 effects reciprocation of thread guide rod 61 for winding the thread on the bobbin and such reciprocating parts including the split nut assembly also lifts rod 71 moving block 52 upwardly with respect to segment bar 50 thereby shortening the stroke of lap lever 56 and of arm 61 to taper the built up yarn body on bobbin or spool 66 as will hereinafter be more fully explained.

Coming back now to drive shaft 39 of cone pulley 38, it will be seen that mounted on said shaft spaced from the large end of said cone pulley is a pulley or sprocket wheel 104 connected by belt or chain 105 with drive wheel 106 mounted on pump drive shaft 107 journaled in supporting bracket 108 and connected to pump 109 which is connected by conduit 110 with a source of thread forming material supply not shown. Said pump 109 is connected by conduit or pipe 111 with the enlarged end of spinneret 112 mounted within 60 chemical tank 67 containing the chemical solution or liquid 113.

It will be observed that the driving connection just described from shaft 39 is controlled by the 70 reversing mechanism in connection with coacting pinion 27 and handle 25 and through the instrumentality of screw 32 connected to belt 37 to gradually increase the volume of flow of the synthetic material through the pump and spinneret 75 in accordance with the increased travel speed of

the thread 65 as it builds up on bobbin 66 and the travel of reciprocating thread guide 61 owing to its shortened stroke and increased reciprocating speed is likewise synchronously controlled in unison therewith. When the bobbin is fully 5 wound, handle 25 is moved to change the reversing mechanism which quickly shifts belt 37 back to its initial position as the vacant bobbin is moved to active or thread receiving position and rotated at its proper initial speed as are also 10 the thread distributing and pump means. With further reference to screw rod 32 it will be noted that same may be provided with grooves 32' at opposite ends of the threaded portion so that in the event the reversing mechanism should not 15 be operated immediately the rod reaches the limit of its movement in either direction the belt 37 could continue to run without damage to the thread or connected parts.

It will be noted that suitably mounted directly 20 below each of the spindles 16 is a rotatable disc spool or bobbin carriage 114 having mounted circumferentially thereof a trio of equi-spaced spool or bobbin shafts 115 journaled in said disc and on one end of the respective shafts is suitably 25 and detachably mounted a respective spool or bobbin 66 and on the opposite ends of said shafts keyed or otherwise suitably secured thereto is a friction drive wheel 116 having a grooved surface 117 to receive and frictionally engage the 30 complementally formed surface 118 of friction drive wheel 17 when carriage 114 is rotated to bring a respective wheel 116 into frictional engagement with wheel 17 to effect rotation of the 35 bobbin or spool 66 as will be apparent.

It has been found expedient to vary the driving speed of wheel 116 to effect variation in the spindle wind of the number of threads per linear inch per second, and which may be accomplished by forming wheels 116 in two complementary sections 119 and 120 connected by screws 121 (only one of which is shown) extending through section 120 and threadedly engageable in opening 122 formed in section 119.

Operation of screw 121 moves said sections to 45 widen or narrow groove 117. Shaft 115 of bobbin 66 is journaled in bearings 123 slidably mounted in said disc carriage 114 and bracket arm 124 suitably carried thereby so that wheel 116 will be maintained in engagement with wheel 17 by springs 125 irrespective of whether the sections 119 and 120 are closely connected or separated since the relative movement of these sections with respect to each other and the coacting surface of wheel 17 constitutes a variable speed 50 drive for bobbin 66.

While the operation of the device would seem to be clear from the above description, it might be well to further state that power is transmitted from the motor to main drive shaft 10 and 60 through gearing 12 to main spindle drive shaft 13 which operates spindles 16 and the friction drive wheels 17 mounted thereon at a constant speed.

Wheels 17 engage drive wheels 116, and 65 through spindles 115 rotate bobbins 66 when the respective bobbins are brought into operative thread winding position. As above stated each of the bobbins 66 normally rotate at a constant speed except when varied by operation of screw 70 121 effecting relative adjustment of the sheave sections 119 and 120 of wheel 116 to vary the number of threads wound on said bobbin per linear inch per second, as hereinbefore explained.

Main drive shaft 10 through reduction gear- 75

ing 19 also drives shaft 18 on which is mounted cone pulley 20 at a constant speed, and shiftable belt 37 connecting cones 20 and 38 drives shaft 39. One end of shaft 39 is connected to disc 46 which is adapted to operate thread distributing rod 61 through the instrumentality of drive rod 47, segmental bar 50, slide block 52, transmission rod 54, lead and lap lever 56 and its connections to rod 61, and from the driving lead and lap lever 56 through shaft 57 to the other levers 56 and their respective distributing rods 61 as will be well understood.

As the thread builds up on a respective bobbin 66 its winding speed is increased and the distributing stroke decreased, which is compensated for as follows: reciprocation of transmission rod 54 effects relative movement of lap hanger 99, yoke arms 85 and ratchet wheel structure 78 connected to split nut 72 threadedly connected to lift rod 71 attached to portion 68 of transmission reach rod 54, and such rocking or reciprocating motion of ratchet wheel 78 effects rotation of said wheel by pawls 98 and which rotates split nut 72 to gradually lift transmission rod 54 and as slide block 52 carried by said rod moves upwardly between segment bars 50 the distributing stroke or movement of arm 61 and hook 64 carrying thread 65 is shortened to taper the ends of the built up thread on bobbin 66 as will be apparent. When a predetermined amount of thread 65 is wound on bobbin 66, collar 71' carried by lift rod 71 engages yoke arms 85 compressing spring 82 spreading split nut 72 and permitting said rod and connected parts to drop back to their initial long stroke position as in the first instance.

Shaft 39 also operates pump 109 to deliver the pulp or other liquid through conduits 110 and 111 to spinneret 112 from which the pulp substance is forced in the form of multifilament threads through chemical 113 in tank 67 forming the rayon or other thread 65 which is distributed over bobbin 66 by hook 64 and rod 61 as hereinbefore described.

At the free end of shaft 18 is the reversing mechanism operable by handle 25 to reverse the direction of travel of threaded rod 32 connected to belt 37 for shifting said belt with respect to the cone pulleys 20 and 38 to vary the driving speed of shaft 39. It is therefore obvious that as the driving speed of shaft 39 is increased, the volume of thread forming material from spinneret 112 to the bobbin and the action of the thread distributing means also operated from shaft 39 will be synchronously advanced in direct proportion to the increased winding speed of the thread during the building up process, and when the bobbin is filled the movement of handle 25 reverses the direction of travel of rod 32, and belt 37 is rapidly shifted back to its initial position, and simultaneously the lift rod mechanism 71 returns the distributing rod operating mechanism to its initial or long stroke position. It is therefore apparent that synchronous control of the pump and distributing means is effected in such a manner that a high thread winding speed may be obtained to greatly increase the thread output without breakage of the thread or variation in thread gauge.

When the spool or bobbin is full, rotation of carriage 114 instantly moves a vacant spool 66 to thread winding position by bringing its respective wheel 116 into driving engagement with 75 spindle friction wheel 17. If it is desired to

change the number of threads per linear inch per time interval as the thread is wound on spool 66 it is only necessary to operate sheave sections 119 and 120 of wheel 116 to vary the spindle speed of said bobbin, as will be clear without further discussion. 5

The operation of clutch handle 22 throws out or brings into operation the pump, thread distributing, and cone variable speed control mechanisms, as desired. It is thought the operation 10 will be sufficiently clear from the above to render further detailed explanation unnecessary.

From the foregoing it will be apparent that I have designed a rayon spinning machine capable of increasing the thread production and operating the thread winding and distributing mechanisms at speeds commensurate with such rate of production and enabling a spindle winding speed beyond that heretofore accomplished without effecting breakage of the thread and causing 20 irregular thread gauge, and at the same time also capable of varying the number of threads wound on the bobbin per linear inch per second without affecting the constant speed of the spindle, said machine being of simplified construction, 25 manufacturable at a reasonable cost, and efficient for the purposes intended.

Although in practice I have found that the form of my invention illustrated in the accompanying drawings and referred to in the above 30 description as the preferred embodiment is the most efficient and practical; yet realizing the conditions concurrent with the adoption of my invention will necessarily vary, I desire to emphasize that various minor changes in details of 35 construction, proportion and arrangement of parts, may be resorted to within the scope of the appended claims without departing from or sacrificing any of the principles of this invention.

Having thus described my invention, what I desire protected by Letters Patent is as set forth in the following claims:

1. A rayon spinning machine comprising means for forming and winding a thread, said means including means for winding the same unit length of thread per layer wound irrespective of the increased diameter of the built-up thread and comprising a thread winding spindle, means for driving the spindle at a predetermined constant speed, thread distributing means associated with said spindle, and means co-acting with said spindle driving means for automatically increasing the output of the thread forming means and automatically controlling the stroke of the distributing means in proportion to the increase in winding speed of the thread during the winding process. 55

2. A rayon spinning machine comprising means for forming a rayon thread, said means including a spinneret, and means for winding the same unit length of thread per layer wound irrespective of the increased diameter of the built-up thread, said means comprising means for delivering the thread forming material to the spinneret, a thread winding spindle, means for driving said spindle, thread distributing means associated with said spindle and means for automatically increasing the thread forming rate of said spinneret and relatively increasing the speed and shortening the stroke of said distributing means in proportion to the increase in the winding speed of the thread during its building up process. 70

3. A spinning machine comprising means for forming and winding the same unit length of 75

thread per layer wound irrespective of the increased diameter of the built-up thread at a spindle speed in excess of three hundred revolutions per minute comprising spindle, a bobbin on which thread is wound driven by the spindle, means for driving said spindle, a thread distributing means, means connected to said first mentioned driving means for operating said distributing means, said means including a distributing bar, a pivoted lever connected to the bar, and means for automatically changing the stroke of the pivoted lever and distributing bar, and increasing the speed of said distributing means and output of the thread forming means directly in proportion to the increase in winding speed of the thread during its building up process.

4. A rayon spinning machine comprising means for winding a thread, said means including means for winding the same unit length of thread per layer wound irrespective of the increased diameter of the built-up thread, and comprising a spindle, a rotatable spool on which thread is wound, a distributing means associated with said spindle, thread delivery means, and means for automatically increasing the output of the delivery means and speed of the distributing means in proportion to the increase in winding speed of the thread during its building up process on said spool and simultaneously affecting shortening of the stroke of said distributing means, and means in connection with said distributing means for automatically returning the stroke controlling elements to their initial long stroke positions at the completion of the winding operation whereby said distributing means will operate at its maximum stroke at the beginning of the winding operation.

5. A rayon spinning machine comprising a bobbin, a bobbin drive, thread forming means, a mechanism for distributing the thread as formed on the bobbin, said mechanism including means for winding the same unit length of thread per layer wound irrespective of the increased diameter of the built-up thread, and comprising a reciprocating distributing bar, means for automatically varying the stroke of the bar in accordance with the thread winding speed, said means including a transmission rod and distributing bar, a pair of segmental bars, means for effecting reciprocation of said bars, a slideable block associated with said bars and transmission rod, and means associated with said transmission rod and block for controlling the reciprocating movement of said distributing bar, and means for automatically increasing the speed at which the thread is formed in direct ratio to the thread winding speed of the bobbin, the thread distributing mechanism and the thread forming means being operatively connected to the bobbin drive.

6. A rayon spinning machine comprising a bobbin, a bobbin drive, thread forming means, a mechanism for distributing the thread as formed on the bobbin, said mechanism including means for winding the same unit length of thread per layer wound irrespective of the increased diameter of the built-up thread, and comprising a reciprocating distributing bar, means for automatically shortening the stroke and increasing the reciprocating speed of the bar in accordance with the thread winding speed, and means for automatically increasing the speed at which the thread is formed in direct ratio to the thread winding speed of the bobbin, the thread distributing mechanism and the thread forming means being operatively connected to the bobbin drive.

7. A rayon spinning machine comprising a bobbin, a bobbin drive, thread forming means, a mechanism for distributing the thread and winding the same unit length of thread per layer wound irrespective of the increased diameter of the built-up thread, said mechanism including a reciprocating distributing bar, means for automatically shortening the stroke and increasing the reciprocating speed of the bar in accordance with the thread winding speed and during the thread winding process, and means in connection with said thread distributing mechanism for automatically returning the stroke controlling elements to their initial long stroke positions at the completion of the thread winding process, and means for automatically increasing the speed at which the thread is formed in direct ratio to the thread winding speed of the bobbin, the thread distributing mechanism and the thread forming means being operatively connected to the bobbin drive.

8. In a rayon machine, an automatic thread distributing control mechanism for distributing the thread as formed on the bobbin, said control mechanism including means for winding the same unit length of thread per layer wound irrespective of the increased diameter of the built-up thread and comprising a drive, a reciprocating distributing bar, a pivoted lever connected to the bar and means for automatically changing the stroke of said lever and bar, said means being automatically operable to restore said bar to its initial stroke movement when the thread building up process on said bobbin has reached a predetermined point.

9. In a rayon machine, an automatic thread distributing control mechanism for distributing the thread as formed on the bobbin, said control mechanism including means for winding the same unit length of thread per layer wound irrespective of the increased diameter of the built-up thread and comprising a drive, a reciprocating distributing bar, a pivoted lever connected to the bar and means intermediate the pivoted lever and drive for automatically shortening the stroke and increasing the speed of the distributing bar, and means connected with said intermediate means and automatically operable to return the stroke controlling elements to their initial long stroke positions upon completion of the bobbin winding operation.

10. A rayon machine, an automatic thread distributing control mechanism for distributing the thread as formed on the bobbin, said control mechanism including means for winding the same unit length of thread per layer wound irrespective of the increased diameter of the built-up thread and comprising a drive, a reciprocating distributing bar, a pivoted lever connected to the bar, and means intermediate the drive and pivoted lever including a transmission rod means and means in connection with said rod for automatically changing the arc between the transmission rod and lever to shorten the stroke of said transmission bar, and means in connection with said transmission rod to automatically return said rod to its initial long stroke operating position upon completion of the thread winding operation.

11. In a rayon machine, a bobbin assembly wherein a trio of bobbins may be selectively brought into contact with a common drive, comprising a friction drive, means in connection with the respective bobbins to engage the friction drive, and means in connection with the bobbins

for varying the speed of a selected bobbin with respect to the speed of said friction drive means.

12. A method of forming and winding rayon threads consisting in forming a thread, winding a thread, and distributing the thread as wound, and co-ordinating the winding, distributing, and

forming in a manner to effect winding the same unit length of thread per layer wound irrespective of the increased diameter of the built-up thread.

JOHN B. DOVE. 5
